UNITED STATES PATENT OFFICE

2,559,139

WIRE CLOTHESPIN

William Wheeler, Coventry, England

Application April 30, 1948, Serial No. 24,286
In Great Britain May 9, 1947

1 Claim. (Cl. 24—139)

1

My main object is to provide an improved clothes peg (i. e., a peg for use in clamping garments, linen, cloths or the like articles to a clothes line when they are to be dried) which will be very efficient in operation and inexpensive to manufacture. A further object is to provide a light and easily-holdable clothes peg so that the housewife or domestic helper can without difficulty carry a bunch of them, selecting one at a time as different articles are being secured to the clothes line.

These and other objects and advantages of the invention will be apparent from a consideration of the following description in which reference is made to the accompanying drawings, wherein:

Figure 1 is an elevation of one form of clothes peg embodying the invention, Figure 2 being a similar view when the clothes peg is being used—the article being clamped against the clothes line being indicated by chain lines;

Figures 3 to 6 inclusive are elevations showing modified forms of clothes pegs; and

Figure 7 is a cross-section, to a larger scale, through any of the clothes pegs, being taken, for example, on the line 7—7 of Figure 6.

In each of the constructions shown the clothes peg is formed of a single length of wire, this preferably being a non-rusting wire, encased in a flexible sheath. Figure 7 shows the wire at 10 encased in a polyvinyl flexible sheath 11, which is of pleasing appearance.

Each length of wire has a main portion 12 which is bent to be substantially of U-shape, having parallel limbs 13, 14 joined to one another by a curved bridging portion 15. In addition, there are substantially parallel reversely-extending spring portions 17, 18 which, as shown by Figure 2, are adapted to yieldingly clamp an article, indicated as a sheet or cloth 19, round a clothes line, indicated at 20. Each of these substantially parallel spring portions 17, 18 is joined to the end of the adjacent limb 13 and 14, respectively, by inclined diverging portions 22, 23 which serve to give a lead to the article and clothes line when entering between the said spring portions 17 and 18.

Furthermore, in each of the constructions one of the spring portions, namely, portion 17 in the various figures, terminates at its inner end with a part 25 which extends transversely across the inward extremity of the other spring portion, namely, portion 18, in order to form a stop for limiting the inward travel of the article.

2

Thus, by this means the user of any of these pegs can carry a bunch of them in one hand and, in a very simple manner, successively place them round a cloth or the like when the latter is being held by the other hand in position against a clothes line.

In the construction of Figures 1 and 2 the transversely-extending part 25 terminates with a loop 27 through which the adjacent limb 14 of the main portion 12 extends with clearance. Furthermore, the inward extremity of the spring portion 18 is formed as a loop 28 through which the transversely-extending part 25 passes with clearance. Thus, the transversely-extending part 25 is slidably engaged with the limb 14 and the inward extremity of the spring portion 18 is slidably engaged with the transversely-extending part 25.

In the construction of Figure 3 the transversely-extending part 25 has a relatively-large loop 30 at its end which encircles both the adjacent limb 14 of the main portion and the spring portion 18.

In the construction of Figure 4 the transversely-extending part 25 terminates with a loop 27 through which the limb 14 slidably extends as in the case of Figures 1 and 2, but the inward extremity 32 of the spring portion 18 does not extend quite as far as the transverse part 25 and is turned away from the spring portion 17 to avoid the likelihood of the cloth or the like being pinched by its extremity.

The construction of Figure 5 differs mainly from that of Figure 1 in that the transverse part 25 terminates short of the adjacent limb 14, being slidably engaged by the hooked end 28 of the spring portion 18. Likewise, the construction of Figure 6 differs from that of Figure 4 mainly in that the transverse part 25 terminates short of the adjacent limb 14 towards which it is directed.

What I claim as my invention and desire to secure by Letters Patent of the United States is:

A clothes peg formed of a single length of wire, said wire having a main portion which is of generally U-shape having parallel limbs, and having substantially parallel reversely-extending spring portions adapted to yieldingly clamp an article against a clothes line, said substantially parallel portions being joined to the ends, respectively, of the limbs of said main portion by diverging portions serving to give a lead to the article when entering between said parallel portions, and one of said parallel portions terminating at its inner end with a part extending directly

across the inward extremity of the other of said parallel portions to form a stop for limiting the inward travel of the article, the inward extremity of said other parallel portion being formed as a loop within which said transversely-extending part slidingly engages.

WILLIAM WHEELER.
